AMUSEMENT DEVICE WITH SEPARABLE OVAL
Angelo Giuliano, 754 Mace Ave., Bronx 67, N.Y.
Filed Oct. 26, 1960, Ser. No. 65,161
14 Claims. (Cl. 46—175)

The present invention relates to a mechanical toy and more particularly to a mechanical toy adapted to be synchronized with music.

Humpty Dumpty is one of the most popular Mother Goose characters and the rhyme which tells his story is known to and recited by all children. His egg-like appearance has been employed for generations in stuffed toys, wall plaques, puzzles, and games. Reference is had to my co-pending application Ser. No. 856,820 filed December 2, 1959.

It is among the principal objects of the present invention to provide a toy Humpty Dumpty which will not only in its egg-form resemble the well-known Mother Goose character, but will act out the falling and breaking-open action described in the rhyme. Further, the descent and cracking will be synchronized with the playing of the Humpty Dumpty song, so that the egg will fall down and break apart when the words of the song reach the appropriate point.

It is another object of the present invention to provide a toy Humpty Dumpty which, after falling apart, may be reassembled automatically in preparation for a repeat performance.

The foregoing and other objects of the invention will be best understood from the following description of exemplifications thereof, reference being had to the accompanying drawings, wherein:

FIG. 1 is a fragmentary side elevational view of one embodiment of the device of the present invention, showing the removable casing only in phantom outline;

FIG. 2 is a plan view of the device of FIG. 1, without casing;

FIG. 3 is an elevational view of the Humpty Dumpty figure when closed;

FIG. 4 is an elevational view similar to FIG. 3, but showing the Humpty Dumpty figure open;

FIG. 5 is a fragmentary side elevational view, similar to FIG. 1, but embodying a modification of the device of the present invention, the casing having been removed for better illustration; and

FIG. 6 is a front elevational view of the modified device of FIG. 5.

Referring now to the drawings, a "Humpty Dumpty" oval structure, indicated generally at 10, is composed of several, for instance three, sections. Two top sections 12 and 14 meet a base section 16 along a generally horizontal, circumferential line 18. The top sections are approximately the same size and shape and meet each other along a generally vertical and central line 20. The meeting lines 18 and 20 are zig-zag cut in a jagged manner to simulate the edges of a broken egg shell. The top sections 12 and 14, as best shown in FIGS. 3 and 4, are movably mounted along a portion of their lower edges to the base section 16 by hinges 22 and 23, respectively. The three sections 12, 14 and 16 fit together perfectly, so that in closed position they have an oval configuration.

Located in the base section 16 is a vertical channel or guide 24, in which an elongated follower pin 26 is arranged for reciprocal movement. One end of each of a pair of arms 28 is mounted for rotation on the pin 26. The other end of the arms 28 is secured in any suitable manner, as by rivets 30, to each of the top sections 12 and 14. When the egg is closed, the pin 26 is positioned at the bottom of the channel 24. If the pin 26 is raised

2

to the top of the channel 24, the arms will urge apart the top sections 12 and 14 to imitate the appearance of an egg broken into three pieces. Of course, since the sections are hinged together, it is merely necessary to lower the pin 26 to reassemble the egg.

In one embodiment of the invention, which is illustrated in FIGS. 1 and 2, the "Humpty Dumpty" oval structure 10 above described is mounted on a carrying member 32. The carrying member 32 is bored to permit sliding along an upright or post 34 which is secured to a platform 36 that supports a removable casing 37.

When the carrying member 32, with its attached oval structure 10, is permitted to fall to the bottom of the upright 34, a stationary vertical pin 38 is positioned to enter an aperture 40 in the carrying member 32 and push up against the pin 26, thereby to "break open" the egg. Conversely, when the carrying member 32 is raised to the upper portion of the upright 34, the pin 26 will strike against an abutment member 42 and be pushed down to the bottom of the channel 24, whereupon the egg will once again be whole. In a modified version, the upper abutment member may be a vertical pin, as shown at 42a in FIG. 5, for abutment with the pin 26 to close the oval structure 10.

In order to synchronize the falling and breaking action with the Humpty Dumpty song, a drive gear 44 operates a driven bevel gear 46, as well as a belt 45 to drive a music source 47 of suitable well-known design, for instance a commercially available music box. The drive gear 44 may be turned by a crank 48 or by the release of a wound spring. The gear 46 carries a trip pin 50 which is timed to strike a plate 52 of a lever arm 54 at the word "fall" in the musical sequence when the "Humpty Dumpty" song is played or at any other predetermined instant.

The lever arm 54 is tiltable about a pivot point 56 and is capable of supporting at one end the carrying member 32 on the post 34. Thus, when contact with the plate 52 causes rotation of the lever arm 54, support is withdrawn from the carrying member 32 and it is permitted to fall freely to the bottom of the post 34. A spring 58 returns the lever arm 54 to its original position.

As was previously described, the egg 10 will "break apart" each time it falls down and may be reassembled by returning the carrying member 32, to which the egg 10 is attached, to the top of the upright 34.

In a second embodiment of the invention, shown in FIGS. 5 and 6, there is provided an automatic pick-up, as well as the automatic release of the "Humpty Dumpty" oval. As in the previous embodiment shown, there is provided the oval structure 10 which is supported on a carrying member 62. The vertical pin 38 which actuates the opening action of the egg and the vertical pin 42a which actuates the closing action of the egg, act as previously described.

FIGS. 5 and 6, which illustrate the second embodiment, show a drive gear 68 which may drive the music device 47. The drive gear 68 is driven by a crank 49 that is mounted on a shaft 51 that carries the gear 68 and operates the belt gear 70 which, in turn, causes the revolution of a belt 72. An idler wheel 74 is positioned to support the other end of the belt 72. The shaft 51 and the shaft of the idler wheel may be journaled in a frame 53. The belt 72 carries a pick-up pin or hook 76 which will raise the carrying member 62 when it reaches the same at the bottom of the upright. The pickup pin 76 is flexible so it will move aside when the carrying member 62 is stopped by the abutment member 66.

When the carrying member 62 is raised, it will make impact at 77 and push aside a cam-shaped hold lever

78. The hold lever 78 will be returned to its original position by a spring 80, and the carrying member 62 will be supported in the upper position by the said hold lever. The belt 72 also carries a pin 82 which is positioned to trip the hold lever 78 at the word "fall," at which time the Humpty Dumpty will drop to the bottom. The proper positioning of the pins 76 and 82 for synchronization with the music may easily be determined. The construction of this embodiment of the invention permits continuous automatic pick-up and release of the Humpty Dumpty as the crank 49 is turned and the song repeated.

It has therefore been shown that the present invention provides a mechanical toy which dramatizes the action described in the Humpty Dumpty story and which does so in synchronization with the Humpty Dumpty song. The toy is arranged for immediate and continuous re-use.

While specific embodiments of the invention have been shown and described in detail to illustrate the application of the invention, it will be understood that the invention may be embodied otherwise without departing from such principles.

Having thus described the invention, what I claim as new and desire to be secured by Letters Patent, is as follows:

1. An amusement device having a plurality of sections forming when closed an oval structure, and hinge means connected to all of said sections and being operable to pivot said sections together movably, whereby said sections may be moved to an open position on said hinge means imitating the appearance of a broken egg.

2. An amusement device having a plurality of sections forming when closed an oval structure, hinge means permanently pivoting said sections together movably, and means operable to move apart said sections, whereby said sections will be tilted to an open position about said hinge means imitating the appearance of a broken egg.

3. An amusement device comprising an oval structure having three sections including a base section and two top sections meeting said base section along a generally horizontal line, said top sections meeting along a generally vertical and central line, hinge means permanently pivoting said sections together movably, and means operable to move apart said sections, whereby said sections will be tilted to an open position on said hinge means imitating the appearance of a broken egg.

4. An amusement device comprising a normally egg-shaped structure having a base section and two top sections meeting along a generally vertical and central line, each of said sections being hingeably mounted along a portion of its lower edge, and separating means operable to move apart said sections comprising a channel defined in a section, a pin arranged for reciprocal movement within said channel, a pair of arms each having one end mounted on said pin and the other end secured to each of said top sections whereby said top sections will be moved to closed relation when said pin is positioned near the bottom of said channel and will be moved apart by said arms when the pin is raised to the top of said channel.

5. An amusement device comprising an upright, an oval structure mounted for ascent and descent on said upright, said oval structure having a plurality of sections, and means effectively operable to urge apart said sections when the oval structure descends along said upright to give the appearance of a broken egg.

6. An amusement device comprising an upright, a normally egg-shaped structure mounted for ascent and descent on said upright, said egg-shaped structure having a plurality of sections, hinge means operable to secure said sections together movably, and means effectively acting to urge apart said sections when the egg-shaped structure descends to a point near the bottom of said upright, whereby said sections will be moved to an open position

on said hinge means to give the appearance of a broken egg.

7. An amusement device, as claimed in claim 6, and means connected to said upright and operable to actuate said separating means to close said sections when the egg structure ascends along the upright.

8. An amusement device, as claimed in claim 7, in which said egg-shaped structure has three sections including a base section and two top sections meeting said base section along a generally horizontal line, said top sections meeting along a generally vertical and central line, and in which said separating means comprises a generally vertical channel, a pair of arms each having one end mounted on said pin and the other end secured to each of said top sections whereby said sections will be moved to closed relation when said pin is positioned at the bottom of said channel and will be moved apart by said arms when the pin is raised to the top of said channel.

9. An amusement device comprising an upright, a normally egg-shaped structure mounted for vertical movement on said upright and having a plurality of sections, hinge means operable to secure said sections together movably, means actuatable to hold releasably the egg-shaped structure near the upper portion of said upright, means operable for releasing said holding means, and separating means operable to urge apart said sections when the egg-shaped structure is released and descends along said upright, whereby said sections pivot to an open position on said hinge means to give the appearance of a broken egg.

10. An amusement device comprising an upright, a normally egg-shaped structure mounted for vertical movement on said upright between upper and lower positions and having a plurality of sections, hinge means operable to secure said sections together movably, means actuatable to hold releasably the egg-shaped structure at the upper portion of said upright, means operable for releasing said holding means, separating means actuatable to urge apart said sections when the egg-shaped structure is released and has descended along said upright to the lower position, whereby said sections pivot to an open position on said hinge means to give the appearance of a broken egg, means operable for raising said egg-shaped structure to the upper portion, and means operable to urge together said sections whereby said sections will move to a closed position.

11. An amusement device comprising a support, an upright secured to said support, a carrying member arranged for vertical movement along said upright between upper and lower positions, an egg-shaped structure mounted on said carrying member, said structure having three sections including a base section and two top sections meeting said base section along a generally horizontal line, said top sections meeting along a generally vertical and central line, separating means operable to move apart said sections comprising a generally vertical channel defined in a section, a pin arranged for reciprocal movement within said channel, a pair of arms each having one end mounted on said pin and the other end secured to each of said top sections whereby said sections will be moved to closed relation when said pin is positioned at the bottom of said channel and will be moved apart by said arms when the pin is raised to the top of said channel, a first abutment member disposed near the base of the support and positioned to push up the said pin within the channel thereby to separate the sections when the egg-shaped structure is near the lower position, a second abutment member disposed near the top of the upright and positioned to push down the said pin within the channel thereby to close the sections when the structure is near the upper position, means operable for holding the carrying member in the upper position, and release means actuatable for releasing the holding means for the descent of the carrying member by gravity to the lower position.

12. An amusement device, as claimed in claim 11, in which there are provided means for automatic pick-up of the egg-shaped structure for return to the upper position.

13. An amusement device, as claimed in claim 11, in which there is provided a driven belt, a trip pin carried on said belt to release said holding means, and a pick-up pin carried on said belt to return said egg-shaped structure to the upper position.

14. An amusement device, as claimed in claim 11,

10

together with, a device producing a sound sequence, said release means being in driven connection with said device and operative to be actuated after a predetermined portion of said sound sequence has been passed.
